(57) **CLAIM**

We claim the ornamental design for a cleaning apparatus, as shown and described in FIGS. 1-6.

DESCRIPTION

FIG. 1 is a perspective view of a cleaning apparatus showing my new design;

FIG. 2 is a top plan view thereof;

FIG. 3 is a bottom plan view thereof;

FIG. 4 is a rear elevational view thereof;

FIG. 5 is a front elevational view thereof; and,

FIG. 6 is a side elevational view thereof.

The broken line showing of the environment is for illustrative purposes only and forms no part of the claimed design. It is understood that the cleaning apparatus is used for cleaning an enclosure retaining water.
